John Bennoch, Orono, Maine.

Letters Patent.

Of the Schedule, referred to in these Letters Patent
and making part of the same, containing a description in
the words of the John Bennoch himself of his improvement
in the Steam Engine.

To all to whom these presents shall come.
Be it known that I, John Bennoch, of Orono, in the County of
Penobscot and State of Maine, have invented a new and useful
improvement in the Steam engine, and that the following
is a full and exact description of the construction and
operation of the said engine as invented or improved by me
Fig. 1. The Steam pipe from the boiler to the Steam box B. C¹ & C² &
Steam pipes from the Steam box B. to the circular cylinders D.D. which
are each made of two half circular pieces and are firmly bolted
on the outer edge of the flange, so as to make a circular cylinder cavity
for the piston to move in. The inner flanges of the cylinders have much
turned off each to permit the thickness of the rims of the wheels E. E.
between them when screwed (or bolted) together E. The axis on which
the wheels E. E. are fixed and are made steam tight by rings of brass
other metal let into a groove turned in the inside, (or side next the shell)
of the inner flange. The rings are pressed to the rim of the wheel as they
wear, by screws passing through the flanges or any other kind of pack-
ing may be used. The piston C. Fig. 5. is made to fit the cylindrical cavity
and one is made fast to the rim of each of the wheels E. E. by pins
projecting from the sides of the piston and fitting into a hole in the
rim of the wheels, and fastened with nuts or keys or in any other
manner found most convenient. Fig. 11. includes cast iron flanges of
the cylinders which when bolted together form a hole on the top to admit
the piston. Also a hole on the side to admit valves which are attached to

the rods I.L. which move them. These valves are made to slide steam tight across the cylindrical cavities which have grooves made for the valves to slide in. After the pistons are put into the tins of the wheels the caps J.J. are screwed through its flanges to the top of the box with a piece cast to the under side to fill up the hole or parting in cylinder made to admit the piston all except room for the valve to slide in. The rods I.L. work through holes in the caps J.J. screwed to the sides of the boxes H.H. and work through packing steam tight and the caps being also steam tight, render the whole when the valves slide steam tight S.S.S.S. are executive wheels on the axis F which move the arms K.K on the shafts I.I. on which are also the segments M.M which are connected with the rods I.L by the chains N.N.N.N. but this may be connected with rack or a variety of other ways. The axis F may be made on one piece or of two pieces joined in the middle by a coupling box as most convenient. On the axis F is a bevel wheel Q which meshes into another bevel wheel P on the axis Q on which is a flat rotary valve turning steam tight in the steam box B, and when revolving alternately shuts and opens the steam pipes C¹ and C² and as the valve is reduced from half of a circle so much longer will the steam pipe be kept open, and the shorter time shut. It must be observed that the pistons are on opposite sides of the wheels, now when the piston in the cylinder in which is inserted the pipe C¹ has passed the end of the pipe and the valve is shut by one of the arms K, and at the same time by the revolving of the flat rotary valve, the steam pipe C¹ is opened and the steam admitted between the valve in the cylinder and the piston, this forces the piston to move from the valve till it passes the hole in the cylinder at R when the steam blows off and leaves the valves free from pressure - it is then drawn back by the other arm K and gives the piston liberty to pass. It will be perceived that just before the piston comes to the place where the steam blows off the piston and that the other wheel has got past the valve in the cylinder and that valve

value is shut and the steam pipe C² opened which makes the piston in the cylinder perform the same operation and carries the other to the place where it was at first. Fig 2 is a section of one half of the cylinder D. H. the box to admit the piston C and the valve T. U. one half of the circular cavity in which the piston revolves & the hole when the steam blows off to which may be attached a pipe to carry the waste steam where ever required V shows the brap or other metal ring which by pushing or fitting to the sides of the rim of the wheel E fig 4 makes it steam tight. W. the holes for the bolts to fasten the two half cylinders together. Fig 3. is a section of the cylinder D. at a right angle to fig 2. showing the unicircular cavity U with the brap ring V and the screws for pushing it forward. Fig 4. the wheel B with the section of the piston C showing the manner in which it is keyed to the rim of the wheel. Fig 5. a separate view of the up piston C. Fig 6. the steam box B with the cover removed to show the revolving steam valve X and the ends of the steam pipes C¹ and C², also the end of the axis & of the bevel wheel P. What I claim as my invention and not previously known in the above described machine is. The using of two cylinders and the arrangement of the valves and pistons so as to produce a constant power, and also the rings of brap or other metal and the method of fitting them into the inner flanges of the cylinders, and the manner of pushing them to the sides of the rims of the wheels so as to render the cylinders steam tight.

In testimony that the above is a full and exact description of the construction and operation of my machine as invented or improved by me I have hereunto set my hand this fifteenth day of August eighteen hundred and thirty-five —

Witnessed
